UNITED STATES PATENT OFFICE.

CARLO GIUFFRÉ, OF DETROIT, MICHIGAN.

SAFETY-GATE.

1,275,418.

Specification of Letters Patent. Patented Aug. 13, 1918.

Application filed March 4, 1918. Serial No. 220,185.

To all whom it may concern:

Be it known that I, CARLO GIUFFRÉ, a subject of the King of Italy, residing at Detroit, county of Wayne, State of Michigan, 5 have invented a certain new and useful Improvement in Safety-Gates, and declare the following to be a full, clear, and exact description of the same, such as will enable others skilled in the art to which it pertains 10 to make and use the same, reference being had to the accompanying drawings, which form a part of this specification.

My invention relates to a safety gate for street cars shown in the accompanying drawings and more particularly described in the 15 following specification and claims.

It is well known that many grave accidents result from the carelessness of drivers of motor driven vehicles in attempting to 20 pass street cars which are about to stop to take on or discharge passengers.

It is therefore one of the objects of this invention to provide street cars with a safety gate adapted to close or substantially close 25 the street between the track and the curb on the side of the car from which it discharges or takes on passengers,—the gate to be under the manual control of the conductor, or motor-man, as may be desired.

Another object of the invention is to provide for illuminating the gate so that it may be readily seen at night by vehicular traffic and by passengers alighting from the car.

Another object of the invention is to provide 35 the gate with a "bumper" on the underside to cushion its descent in order that if in lowering the gate it should contact with anyone who might carelessly get in its path it would cause them no injury.

With the foregoing and other objects in view which will appear as the description 40 proceeds, the invention resides in the combination and arrangement of parts and in the details of construction hereinafter described and claimed, it being understood that 45 changes in the precise embodiment of the invention may be made without departing from the spirit of the invention.

In the accompanying drawings:—

Figure 1 is an end elevation of a street car showing the safety gate as it would appear when lowered:—its supporting bracket being indicated in section to more clearly disclose the relation of the parts.

Fig. 2 is a similar elevation with the gate raised.

Fig. 3 is a horizontal sectional and plan view of the end of a car body showing the operating mechanism in dotted lines.

Fig. 4 is a diagrammatic plan view of a 60 street showing a car at a street corner intersection, with the gate lowered to close the driveway between the track and the street curb.

Fig. 5 is a detail cross-sectional view 65 through the housing inclosing the gearing connecting the vertical shaft with the shaft for supporting the gate.

Referring now to the letters of reference placed upon the drawings:—

A denotes a car and B its rear platform. C designates a vertically disposed shaft supported in suitable journals, adapted to be manually rotated by means of an operating lever C' secured to its upper end. D indicates a beveled gear keyed to the lower end of the shaft in mesh with a like gear E carried by the relatively short shaft E' located below the floor of the car. E² indicates a beveled gear at the opposite end of 80 the shaft E' in mesh with a gear G on the end of the shaft G'—extending longitudinally beneath the car. F indicates a hood or casing inclosing the gears. To the rearwardly projecting end of the shaft G' is fitted an arm or gate H adapted to be rocked from a vertical to a horizontal position and back to its initial position through the operation of the manually operated lever C', as 85 will be readily understood.

Set in the gate or arm is an electric lantern H' connected by suitable wiring with a source of electric power (not shown) the lantern being preferably fitted with a red globe with the word "Stop" or other suitable warning-word displayed thereon. Projecting downwardly from the gate is a "bumper" comprising a resilient rod I, secured at its ends to the gate by bolts or other fastening means.

J denotes a bracket secured to the car frame by suitable channel irons or bars J' having a vertical wall J² to limit the upward swinging movement of the gate. J³ denotes a horizontal wall of the bracket, designed to 105 support the gate when lowered to close the driveway L between the curb M and the side of the car.

Having indicated the several parts by reference letters the construction and operation of the device will be readily understood.

Upon stopping the car at a street inter-

section, either to take on or discharge passengers, the conductor or motorman having charge of the operation of the gate actuates the controlling lever to lower the gate, thus 5 closing the street against vehicular traffic between the car and the curb on the side from which passengers leave or board the car.

Passengers may then leave or board the car in safety, knowing that vehicles will not 10 attempt to pass while the car is at rest. Upon giving the signal to go on, the gate is elevated, remaining in that position until the car makes the next stop.

To avoid any chance of injury to carelessly inclined persons who may dodge under the gate while it is being lowered the "bumper" is provided to cushion the blow of the descending gate.

On the bar of the gate suitable warning 15 words such as "Safety first" or words of like import may be displayed if desired.

Having thus described my invention what I claim is:—

1. In a device of the character described, 20 a car, a transversely swinging arm or gate pivoted to a shaft supported by journals secured to the car frame, said arm being adapted to project from the side of the car across the driveway between the car and the 25 street curb, whereby the driveway may be closed against vehicular traffic, and manually operated means for actuating said arm or gate.

2. In a device of the character described, 30 a car, a swinging gate adapted to close the street between the car and curb against vehicular traffic, a rock-shaft suitably journaled in the car frame to which said gate is secured, a vertical shaft geared to the rock-shaft, and a lever secured to the 35 vertical shaft for manually operating said gate.

3. In a device of the character described, 40 a car, a swinging arm adapted to project across the driveway adjacent to the car to close the street, a rock shaft to which said arm is secured supported in journals secured to the car frame, a warning lamp mounted in said arm, and means for manually operating the rock shaft.

4. In a device of the character described, 45 a car, a swinging arm adapted to close the driveway between the car and the street curb, a bracket having an upstanding wall to limit the movement of the arm in one direction and a horizontal wall to serve as a support for the arm when lowered, means for securing the bracket to the car frame, and means for manually actuating said 50 swinging arm.

In testimony whereof I sign this specification in the presence of two witnesses.

CARLO GIUFFRÉ.
